UNITED STATES PATENT OFFICE.

DAVID S. BRAGDON, OF DURHAM, ASSIGNOR OF ONE-FOURTH TO ZEBULON K. HARMON, OF PORTLAND, MAINE.

COMBINED NECKTIE AND SHIRT-BOSOM.

SPECIFICATION forming part of Letters Patent No. 364,891, dated June 14, 1887.

Application filed December 15, 1886. Serial No. 221,696. (No model.)

To all whom it may concern:

Be it known that I, DAVID S. BRAGDON, of Durham, in the county of Androscoggin and State of Maine, have invented a Combined 5 Necktie and Shirt-Bosom, of which the following is a specification.

The object of my invention is to unite a detached shirt-bosom with an article of ornamental neck-wear in such a manner that the 10 appearance of both may be secured at less expense than would be incurred by purchasing and wearing these two articles in the usual way.

The invention is intended to economize 15 both in first cost and in laundry-work, as the bosoms are not of large size and can be easily cleaned when removed.

Of the drawings illustrating my invention, Figure 1 is a front view of the whole as arranged for use. Fig. 2 is a view of the back of Fig. 1. Fig. 3 is a front view of the bosom detached. Fig. 4 is a rear view showing the water-proof covering and means for attaching the same.

25 Similar letters of reference indicate corresponding parts.

In carrying out my invention I make use of a kind of bosom-holder, A B C, Fig. 1, which performs the double duty of presenting 30 an ornamental exterior similar to the so-called "neckscars" or "neckties" now in use, and of holding a bosom in place by means of suitable supports at the back of the holder. This ornamental holder is stiffened with pasteboard 35 or other material, and has its front surface covered with silk, or any material that would give to it a neat appearance. It may be ornamented with a bow or other suitable device, and has an opening, described by the 40 letters *c d f*, Fig. 1, through which the bosom is seen.

The bosom shown at Fig. 3 is much smaller than an ordinary shirt-bosom. It may be made of linen, paper, celluloid, or other suitable material; is made somewhat larger than

the opening in the bosom-holder, and held close to the back of said holder in such a way that it may be easily removed when soiled.

I am aware that there is nothing new in a false or removable shirt-bosom; but I believe 50 that a bosom so constructed that its edges may be concealed in and the bosom supported by an article of ornamental neck-wear is new.

The back of the bosom-holder A B C is covered with the piece shown at *g h i*, Fig. 2, 55 which piece is covered with oiled silk or other water-proof material to protect the bosom from sweat. The bosom-holder and the piece *h i* are joined together near their edges, thereby forming a kind of sheath in which the bosom 60 is held.

The whole device is held in place close to the shirt-collar by means of an elastic band passing around the neck of the wearer, or by other suitable means.

The bosom shown in Fig. 3 is removed from the holder by simply drawing it out at the top from between the front, A B C, and the back piece, *g h i*.

Having thus described my invention, I claim 70 as new and desire to protect by Letters Patent—

1. The combination, with a bosom-holder consisting of a front piece having a central opening and an attached back piece covering 75 said opening, of a removable bosom inserted between the two, and a water-proof covering permanently attached over said back piece, substantially as described.

2. The combination, with the ornamented 80 front piece, A B C, having a central opening, and provided with a back piece, *g h i*, covering said opening, of a removable bosom, *c*, inserted between the back and front, and a water-proof covering permanently attached 85 over the back piece, substantially as described.

DAVID S. BRAGDON.
